UNITED STATES PATENT OFFICE

FRANK R. PAGE, OF BROOKLYN, NEW YORK, ASSIGNOR TO SCOTT & WILLIAMS, INCORPORATED, OF NEW YORK, N. Y., A CORPORATION OF MASSACHUSETTS

LOOP-POSITIONING DEVICE

Application filed August 8, 1929. Serial No. 334,378.

This invention has to do with mechanism for properly positioning, on the needles of a circular knitting machine preparatory for knitting, the loops forming the end course 5 of a previously formed piece of fabric, usually one transferred from another machine. A common instance of such a transferred fabric is a ribbed top for a stocking. Such a mechanism includes a cam that is set near the 10 needles to engage the loops as they revolve past the part of the circle at which the web-holders are retracted. This cam presses the loops down below the level of the holding down hooks of the web-holders so that when 15 the needle rises to take yarn for the new loop, the old loop will be held down.

The primary objects of this invention are to avoid delay in the beginning of the knitting of the courses which are to be added to 20 the pre-formed fabric and to make the control of the cam that depresses the loops automatic and simultaneous with other operations which precede the actual beginning of knitting. Speaking more specifically, the invention makes the loop positioning means independent of the movement of the latch ring to its operative position and independent also of other parts of the machine, so that the 25 action of the presser cam need not await the complete lowering of the ring. Hence there need be no extra rack of the pattern drum and no wasted revolutions of the needles, after 30 the latch ring is lowered, to permit the loops to be positioned properly before knitting begins. Another object attained is that the 35 proper positioning of the loops is kept from being adversely affected by any vertical movements of the needle cylinder which may occur while the loops are being pressed down to the proper level on the needles.

In the accompanying drawings, to which reference is made in the course of the following description of a preferred form of the invention therein illustrated,

Figure 1 is a view, in elevation, of a part of a Scott and Williams circular knitting machine showing the relation between the loop positioner, the latch ring, the knitting instruments and the main pattern drum, all 40 being in the positions which they occupy

when the loops are being pressed down to the proper level. The front portion of the latch ring is shown as being broken away in part.

Figure 2 is a similar view of the same parts, 55 showing the position which they occupy during the knitting, after the latch ring has been fully lowered and the loop positioner retracted.

Figure 3 is a similar view showing the 60 same parts in the positions assumed after the latch ring has been fully lifted and the loop positioner has been carried up by the latch ring to clear the space above the needle cylinder.

Figure 4 is a top plan view of a portion of the needle cylinder of the same machine showing the loop positioning cam in operative position with respect to the needles, the mechanism which moves the said cam not being 65 fully shown.

Figure 5 is a detail view of a single web-holder and associated needle, the web-holder being in retracted position, the purpose of this view being to show the position on the 70 needle of a loop in the end course of a fabric just transferred to the needles and not properly positioned to begin knitting.

Figure 6 is a similar view showing the 75 position of the loop as it is passing under the lowest part of the presser or loop positioning cam.

Figure 7 is a view of a single web-holder and associated needle, the web-holder being in advanced position, showing the position of 80 the loop depicted in Figures 4 and 5 but after passing under the loop positioning cam.

Figure 8 is a detail view, in elevation, looking from the center of the upper end of the needle cylinder toward the area in 85 front of the throat plate where the web-holders are retracted, showing the loop positioner cam and the way in which the loops are pressed down on the needles as they pass under the cam.

The invention is illustrated and described here as it is used with a Scott and Williams machine of the B type, designed to receive a ribbed top, knit on another machine, and to knit the rest of the stocking. There is, how- 90 95 100

ever, no dependency on this particular machine and no limitation to this particular use.

There is the usual revolving needle cylinder 260 with a circular series of needles N working in vertical grooves in its outer surface under the control of cams (not shown here) arranged on the bed plate D. A ring 257, rotating with the needle cylinder, carries a series of loop-forming sinkers or web-holders 292 which have nebs or holding down hooks 291. The main pattern drum 120 is advanced at intervals and in so turning the cam lugs on its face control in the desired time relation the various operations of the machine.

15 The latch ring 550 is pivoted in the usual way on a stud 552 in the post 401 which is supported on the bed plate D, and one or more yarn fingers F are pivoted on the arm 555 which extends upwardly from a part 20 of the latch ring. The toes of these fingers rest on the throat plate 559 when feeding to the needles and are moved toward and away from this throat plate by thrust rods (not 25 shown here) actuated by suitable lugs on the pattern drum.

The latch ring 550 is swung toward and away from its position over the needle cylinder by a thrust rod 461 pivoted to the arms 30 553 which reach from the ring itself to the stud 552 about which the ring swings. The lever 461 is guided and braced by a comb 452 mounted on the fixed stud 450 and its lower end rests on the main drum 120 in 35 the path of a cam lug 501. When this lug lifts the lever the latch ring is swung upwardly to the position shown in Figure 3 and when the lever rests on the face of the drum the ring assumes its operative position (shown in Figure 2) over the needle cylinder. At the end of the knitting, the ring is 40 lifted so that it is in its upper position when the ribbed top, or other previously knit part of an article, is transferred to the needles N for the next cycle of the machine.

45 The cam lug 501 which thus controls the latch ring is a peaked one with sloping sides. The peak is located, with respect to the other cam lugs on the drum, at the zero point, that is, at such a point that when the drum comes 50 to rest after a stepped rotation the peak of the cam lies beneath the thrust rod 461 thereby lifting the latch ring. On the first advance step of the pattern drum, the ring is 55 swung downwardly part way to the position shown in Fig. 1 as the thrust rod 461 rides down the sloping face of the cam lug 501. On the second rack of the drum the cam lug 501 moves from beneath the thrust rod 461 and 60 allows the latch ring to come to its lower or operative position (Figure 2).

The loop positioning cam 2 is formed as an offset at the end of a downward extending rod 3 which is adjustably held by a set screw 65 4 independently of the latch ring. Its rear

part, near the pivot stud, lies alongside of the arms 553 of the latch ring while its forward part 6 extends across the adjacent side of the latch ring to a point above and slightly to the side of the throat plate. A rod 8 70 adjustably held in the arm 5 by a set screw 9 rests on the top of the sinker cap 300 when the arm 5 is swung downwardly. By properly adjusting the positions of the rods 3 and 8 on the arm 5, the loop positioner is 75 put in correct position with respect to the needles and web-holders when the rod 8 rests on the cap 300. This position is such that the cam 2 lies close to the inside of the needles at that part of the circle at which the 80 web-holders are retracted and with its lower edge 2^a sloping downwardly in the direction in which the needles rotate. The lower end 2^b of this inclined edge 2^a lies at a level just below the level of the nebs 291 of the web-holders.

For swinging the arm 5 about the stud 552 there is a thrust rod 462 pivoted at its upper end to a lug 10 on the under side of the arm 5 and resting at its lower end on the pattern 90 drum 120 in the path of a cam lug 502. This lug is continuous for the greater part of the drum circumference and therefore prevents the arm 5 from being fully lowered during the greater part of the cycle of the machine. 95 It is inter-related with the cam 501 by reason of having a gap about in register with the said cam with the result that as the thrust rod 461 rides off the lug 501, dropping the latch ring to its operative position, the thrust rod 462 is lifted by the leading edge 502^a of the lug 502. The final result is that the loop positioner is moved out of operative position as the latch ring goes into its lower position. The trailing end 502^b of the lug 105 502 is back of the forward end of the latch ring lug 501.

With the peak of the cam 501 beneath the thrust rod 461 (Figure 3), the latch ring is held in its uppermost position, and by reason of its engagement with the forward part 6 of the arm 5 which overlies the ring, the arm 5 is likewise held clear of the needle cylinder. (See Figure 3.) This position of the arm 5 is higher than that determined by the cam 502 and, of course, could be brought about by a suitably high cam 502 but that is not necessary due to the arms overlying the latch ring. On the first rack 115 of the pattern drum, the cam lug 501 is moved until the thrust rod 461 rests about half way down its rear face (Figure 1) putting the latch ring in an intermediate position in which it is below and clear of the arm 5. 120 This restores the arm 5 to control from the pattern drum alone and, since at this time the cam lug 502 is not beneath the rod 462, the latter rests on the face of the drum and the loop positioning cam 2 is put in its oper- 125 130

ative position with the rod 8 resting on the sinker cap 300.

In this position, the needle engaging loops of the fabric transferred to the machine are depressed by the cam below the nebs 291 of the web-holders as the needles rotate. If the needle cylinder is shifted vertically for any reason, as frequently occurs, during the time the loop positioner is in this position, there is no disturbance of the action of the cam as the arm 5 then swings with the movement of the cylinder, keeping the cam 2 in operative position with respect to the needles and web-holders.

On the next rack of the drum, the cam 501 moves from beneath the rod 461 and causes the latch ring to drop to its final position over the needle cylinder, while at the end of the same rack the cam lug 502 rides under the rod 462 and lifts the loop positioner to an idle position clear of the knitting instrumentalities. (Fig. 2.) The same rack is availed of to lower the yarn finger so that knitting can begin at once. Were it not for the fact that the positioning of the loops is accomplished before the latch ring is fully lowered, it would be necessary to defer the lowering of the yarn fingers and the beginning of the knitting until at least one complete revolution after the lowering of the latch ring. That would involve giving the pattern drum an extra rack to initiate the knitting, either by a special pawl at the end of one revolution or at the end of the usual four revolutions before another rack would be taken. In the latter case there would be three idle revolutions and in either case the additional space required on the drum and the other mechanism needed would make it most undesirable. The present construction is therefore of distinct advantage. It may be noted in passing that it is the common practice to lower the latch ring in two stages as described here. For that reason, lowering of the loop pressing cam during one of these stages and its raising during the other requires no additional racks of the pattern drum.

After the knitting is completed, the cam 501 again comes under the rod 461 and lifts the latch ring in one rack to its upper position. The latch ring takes with it, from the idle position just described, the arm 5 which carries the loop depressing cam 2. The space above the needle cylinder is therefore clear to facilitate the removal of the knitted article and the transfer of a new fabric.

An important characteristic of the construction described is that the loop positioner is structurally independent of the latch ring and of other mechanisms, being separately mounted, and it therefore is independent in respect of its movement into and out of operative position, although it is moved in timed relation to other operations of the machine.

It is true, of course, that in swinging past the intermediate position (Figure 1) to the position clear of the needle circle the latch ring does carry the arm 5 with it and thus there is a certain dependency but that comes only after both the ring and the cam are already removed from operative position and is therefore immaterial. It is merely a movement from one idle position to another to clear the space above the needle cylinder. It is obvious that by suitably shaping the arm 5 and the cam 502 even this dependency could be avoided but as it is not undesirable and does have certain obvious advantages it is preferable to construct the arm as shown.

It is also an important characteristic of this construction that the cam, when in operative relation to the needles and web-holders, is not affected in that relation by vertical shifting of the needle cylinder. This comes about from the fact that the cam is supported on a part that moves vertically with the cylinder, hence the cam itself moves up and down with the cylinder, maintaining its lowest edge beneath the level of the holding down hooks of the web-holders.

I claim—

1. In a circular knitting machine having a needle cylinder, a circular series of needles with intercalated web-holders, a latch ring movable to and from its operative position, a cam for depressing on said needles the loops of a fabric impaled thereon, and pattern controlled means for putting said cam in operative position independently of movement of said latch ring to its operative position.

2. In a circular knitting machine having a needle cylinder, a circular series of needles with intercalated web-holders, a latch ring movable to and from its operative position, a cam for depressing on said needles the loops of a fabric impaled thereon and pattern controlled means for moving said cam to and from its operative position independently of movement of said latch ring to its operative position.

3. In a circular knitting machine having a needle cylinder, a circular series of needles with intercalated web-holders, a latch ring and a cam for depressing on said needles the loops of a fabric impaled thereon, in combination with separate means for moving said latch ring and said cam to their respective operative positions and inter-related cam means controlling said separate means.

4. In a circular knitting machine having a revolving needle cylinder, a circular series of needles with intercalated web-holders, a pattern cam drum for controlling operations of the machine in definite inter-relation, a latch ring and a cam for depressing on the needles the loops of a fabric impaled thereon, in combination with separate means for moving said latch ring and cam to their respective opera-

tive positions, said means being controlled by said pattern cam drum.

5. In a circular knitting machine having a revolving needle cylinder, a circular series of needles with intercalated web-holders, a cam for depressing on the needles the loops of a fabric impaled thereon, a pattern mechanism for controlling operations of the machine in definite inter-relation, and means controlled 10 by said pattern mechanism for moving said cam to and from its operative position, said means being structurally independent of other pattern controlled mechanisms.

6. In a circular knitting machine having a 15 needle cylinder, a circular series of needles and intercalated web-holders, a cam for depressing on the needles the loops of a fabric impaled thereon, a pivoted latch ring and a separate support and operating means for 20 said cam to move said cam between its operative position and an idle position independently of said latch ring.

7. In a circular knitting machine having a needle cylinder, a circular series of needles 25 and intercalated web-holders, a cam for depressing on the needles the loops of a fabric impaled thereon, a pivoted latch ring and a support for said cam pivoted independently of said latch ring, together with inter-related cam means for moving said ring and 30 said cam about their pivots.

8. In a circular knitting machine having a revolving needle cylinder, a circular series of needles with intercalated web-holders, a 35 latch ring and a cam for depressing on the needles the loops of a fabric impaled thereon, a pattern mechanism for controlling operations of the machine in definite inter-relation and including means for moving said cam 40 to its operative position while said latch ring is in an idle position.

9. In a circular knitting machine having a revolving needle cylinder, a circular series of needles with intercalated web-holders, a 45 latch ring and a cam for depressing on the needles the loops of a fabric impaled thereon, a pattern mechanism for controlling operations of the machine in definite inter-relation and including means for moving said cam 50 to its operative position while said latch ring is in an idle position and for moving said cam therefrom as the latch ring is put into its operative position.

10. In a circular knitting machine having 55 a revolving needle cylinder, a circular series of needles with intercalated web-holders, a pivoted latch ring and a separately pivoted arm with a cam for depressing on the needles the loops of a fabric impaled thereon, an 60 intermittently moved pattern mechanism for controlling operations of the machine in definite inter-relation and means for dropping said latch ring to operative position in two steps of said mechanism and for moving said 65 cam to its operative position on the first of

said steps and away from said position on the second.

11. In a circular knitting machine having a revolving needle cylinder, a circular series of needles with intercalated web-holders, a pivoted latch ring and a pivoted arm extending across said latch ring and carrying a cam for depressing on said needles the loops of a fabric impaled thereon, a pattern mechanism for lowering said latch ring in two steps and for lowering said arm to put said cam in operative position on the first of said steps and away therefrom on the second, said arm being adapted to be lifted by said latch ring from its idle position determined by said pattern mechanism and to be restored to control by said mechanism on the first step of lowering said latch ring. 70 75 80

12. In a circular knitting machine having a needle cylinder, a circular series of needles with intercalated web-holders, said web-holders, needles and cylinder being capable of vertical movement as a unit, a cam for depressing on the needles the loops of a fabric impaled thereon, said cam being adapted, 85 when in operative position, to move vertically with said cylinder and web-holders to maintain its relation thereto.

13. In a circular knitting machine having a needle cylinder, a circular series of needles with intercalated web-holders, said web-holders, needles and cylinder being capable of vertical movement as a unit, and a cam for depressing on the needles the loops of a fabric impaled thereon, said cam being supported 90 in operative position by a part moving vertically with said vertically moving elements. 95 100

14. In a circular knitting machine having a revoluble needle cylinder, a circular series of needles and intercalated web-holders all capable of vertical movement as a unit, a latch ring movable to and from its operative position and a pivoted arm with a cam for depressing on the needles the loops of a fabric impaled thereon, said arm having a member adapted to rest on a part moving vertically with the needle cylinder to support said cam in operative position. 105 110

15. In a circular knitting machine having a revoluble needle cylinder, a circular series of needles and intercalated web-holders all capable of vertical movement as a unit, a pivoted latch ring adapted to be moved to operative position in two stages, and a pivoted arm extending across said latch ring, said arm having a depending cam for depressing on said needles the loops of a fabric impaled thereon and having a member adapted to engage a part moving with said vertically moving parts and to space said arm from said ring when the latter is partly lowered and said arm is fully lowered. 115 120 125

In testimony whereof I have signed my name to this specification.
